US0D1058745S

(12) **United States Design Patent** (10) **Patent No.:** **US D1,058,745 S**
(45) **Date of Patent:** **** Jan. 21, 2025**

(54) **WATER PURIFIER**

(71) Applicant: **BLANCO GmbH + Co KG**,
Oberderdingen (DE)

(72) Inventor: **Thomas Funke**, Eppingen (DE)

(73) Assignee: **BLANCO GmbH + Co KG**,
Oberderdingen (DE)

(**) Term: **15 Years**

(21) Appl. No.: **29/828,408**

(22) Filed: **Feb. 25, 2022**

(30) **Foreign Application Priority Data**

Aug. 26, 2021 (EM) 008662571-0002

(51) **LOC (15) Cl.** **23-01**

(52) **U.S. Cl.**

USPC **D23/207**
